Term of patent 14 years

Claims priority, application Italy Apr. 13, 1968

Int. Cl. D12—14, 99

U.S. Cl. D14—6

Fig.-1

Fig.-3

Fig.-2

Fig. 5

FIGURE 1 is a front view of an external driving mirror for motor vehicles, showing my new design;

FIGURE 2 is a top plan view thereof;

FIGURE 3 is a rear view thereof;

FIGURE 4 is a right side view thereof;

FIGURE 5 is a left side view thereof; and

FIGURE 6 is a bottom plan view thereof.

I claim:

The ornamental design for an external driving mirror for motor vehicles, as shown.
